UNITED STATES PATENT OFFICE.

EDWARD HALLER, OF CLEVELAND, OHIO, ASSIGNOR OF ONE-FOURTH TO JOHN J. KOLLER AND ONE-FOURTH TO LADIMIR HEROLD, BOTH OF CLEVELAND, OHIO.

CIGAR-ASH PROTECTOR.

979,944.

Specification of Letters Patent. Patented Dec. 27, 1910.

Application filed April 11, 1910. Serial No. 554,586.

To all whom it may concern:

Be it known that I, EDWARD HALLER, a citizen of the United States, residing at Cleveland, in the county of Cuyahoga and

5 State of Ohio, have invented a certain new and useful Improvement in Cigar-Ash Protectors, of which the following is a full, clear, and exact description, reference being had to the accompanying drawings.

10 My invention relates to a class of articles which may be designated as an attachment for use with a cigar when the same is being smoked.

15 The object of the invention is to provide a protecting envelop for the cigar which will cover all of the body of the cigar except that portion which is placed within the mouth of the smoker.

20 The device provides a protecting cover for the cigar, and at the same time catches all ashes which may drop from the smoked end of the cigar and thus prevents their falling upon the floor if the cigar be smoked within the house or prevents their falling upon the 25 clothes of the smoker.

25 My device once being secured upon the cigar need not be removed for adjustment but will permit the smoking of the entire cigar after the device is once placed thereon.

30 Reference should be had to the accompanying drawings, in which—

35 Figure 1 is a perspective view of my device secured to a cigar; Fig. 2 is a perspective view of the holder when open; Fig. 3 is a section upon the line 3—3 of Fig. 1; and Fig. 4 is a section upon the line 4—4 of Fig. 1.

40 The body of the holder consists of two parts 1 and 2 which parts at their rear ends are carried upon parts of a collar 3 and 4 which are hinged together at 5, as will be clearly seen from Figs. 2 and 3.

45 The parts 1 and 2 are formed of a reticulated material preferably a wire screening and are shaped so that when closed they will embrace the body of a cigar. The portion 1 carries a circular end member 6 with which the end of the member 2 co-operates when the device is closed and thus prevents ashes from falling from the end of the holder. The part 4 of the collar is provided with a tongue 7 which is formed with a ridge therein, indicated at 8. The portion 3 of the collar is formed with a series of depressions 9 with which the ridge 8 may co-operate. By

providing the three ridges it is possible to grip the cigar tightly when the collar is closed and thus provide for a variation in the size of different cigars.

50 As shown in Fig. 4 the edges of the members 1 and 2 overlap each other and thus prevent any spreading apart of the members 1 and 2.

The reticulated portion is of such mesh that it will hold the cigar ashes and yet will 65 permit the free passage of air through the same.

60 The outside of each of the collar members 3 and 4 is provided with a covering of heat insulating material 9. This material may 70 be of any well known substance and in practice I prefer to use asbestos.

75 It will be noted that with the device which I have provided, it is unnecessary to adjust the device after it has once been placed upon the cigar. In this respect it differs from all devices of its character which are at present known.

Having thus described my invention, what I claim is:

80 1. A cigar ash protector consisting of a two part reticulated covering for said cigar and extending from one end to substantially the other end thereof, and means for holding said reticulated covering upon the cigar, with the edges of the two parts overlapping.

85 2. A cigar ash protector, consisting of a two-part reticulated member, means for holding the said parts together and for securing them to the cigar, with their longitudinal edges overlapping.

90 3. A cigar ash protector comprising two reticulated members which are shaped to conform to the shape of the cigar, a collar to which the said members are secured at one end, the said collar being hinged, and means upon the collar for fastening the two parts thereof together.

95 4. A cigar ash protector comprising two rounded members, the edges of which overlap when they are in place upon the cigar, a collar to which the ends of the said members are secured, said collar being formed of two parts which are hinged together, and means upon the collar for securing the two portions thereof together.

100 5. A cigar ash protector comprising two reticulated members which are adapted to envelop a cigar, a two-part collar, each of the said members being secured to one of

- the parts of the collar, a tongue projecting from one of said collars, a ridge upon said tongue, and depressions formed in the other part of the said collar with which the ridge on the tongue may coöperate and grip the cigar.
6. A cigar ash protector comprising two coöoperating reticulated members which envelop a cigar, a clamping member with which said reticulated members coöperate, and heat insulating material carried by said clamping members.
- 10 7. A cigar ash protector comprising two

reticulated members which coöperate to envelop the cigar, a hinged two-part collar 15 to which the said members are secured, means for securing the parts of the collar together, and an asbestos covering for the outside of the collar.

In testimony whereof, I hereunto affix my 20 signature in the presence of two witnesses.

EDWARD HALLER.
